UNITED STATES PATENT OFFICE

JOSEPH H. CROSBY, OF JACKSONVILLE, FLORIDA.

DESIGN FOR A BODKIN.

No. 37,871.

Specification for Design.

Patented March 6, 1906.

Application filed January 24, 1906. Serial No. 297,720. Term of patent 7 years.

To all whom it may concern:

Be it known that I, JOSEPH H. CROSBY, a citizen of the United States, residing at 215 Laura street, Jacksonville, Duval county, State of Florida, have invented a new, original, and ornamental Design for a Bodkin, of which the following is a specification, reference being had to the accompanying drawing, which shows a plan of the bodkin.

I claim—

The ornamental design for a bodkin as shown.

JOSEPH H. CROSBY.
